Primary Examiner — Sandra Morris(74) Attorney, Agent, or Firm — Seth D. Levy; Davis Wright Tremaine LLP(57) CLAIM

The ornamental design for a bottle in female form, as shown and described.

DESCRIPTION

FIG. 1 is a front view of a bottle in female form of the present invention;

FIG. 2 is a rear view thereof;

FIG. 3 is a top view thereof;

FIG. 4 is a bottom view thereof; and,

FIG. 5 is a perspective view thereof.

The shade lines in the Figures show contour and not surface ornamentation.
